CLAIM

The ornamental design for an activity monitoring device, as shown and described.

DESCRIPTION

FIG. 1 is a top perspective view of an embodiment; FIG. 2 is a bottom perspective view of the embodiment; FIG. 3 is a top view of the embodiment; FIG. 4 is a bottom view of the embodiment; FIG. 5 is a left side view of the embodiment, the right side view being a mirror image thereof; FIG. 6 is a back view of the embodiment; and, FIG. 7 is a front view of the embodiment.

The broken lines immediately adjacent the shaded areas represent the bounds of the claimed design while all other broken lines are directed to environment and are for illustrative purposes only; the broken lines form no part of the claimed design.

1 Claim, 6 Drawing Sheets
